UNITED STATES PATENT OFFICE.

CHARLES F. WALther, OF BUFFALO, NEW YORK, ASSIGNOR TO THE
NIAGARA RADIATOR COMPANY, OF SAME PLACE.

DESIGN FOR A RADIATOR.

SPECIFICATION forming part of Design No. 31,950, dated December 5, 1899.

Application filed October 13, 1899. Serial No. 733,533. Term of patent 14 years.

To all whom it may concern:

Be it known that I, CHARLES F. WALther, a citizen of the United States, residing at Buffalo, in the county of Erie and State of New York, have invented and produced a new and original Design for a Radiator, of which the following is a specification.

The accompanying drawing is a perspective view of a radiator embodying my new and original design.

The exposed or end loop L of the radiator is formed with two columns A A, separated by a space B, around which space is a groove C. The upper part of the radiator-loop, (designated by D,) the part which is above where the two columns A come together and where the groove C curves around the upper end of the open space B, is of greater height than it has heretofore been customary to make this part of the radiator, and this is important, as it gives a comparatively large space above the

groove C and opening B, upon which space is placed a handsome ornament, as the wreath d. The vertical dimensions 3 of this space from the upper end of the opening B to the top of the radiator-loop is considerably greater than the width of either one of the columns A from the vertical center of the open space to the outer edge of the loop and represented by the dotted line 2.

The distinguishing and characteristic feature of this design is the configuration of a two-column loop, and particularly the upper part thereof, as has been described.

What I claim, and desire to secure by Letters Patent, is—

The design for a radiator, substantially as shown and described.

CHAS. F. WALther.
